CRACKING HYDROCARBON OILS

Howard Dimmig, New York, N. Y., assignor to
Gasoline Products Company, Inc., Newark, N.
J., a corporation of Delaware

Application September 8, 1934, Serial No. 743,219

1 Claim. (Cl. 196—47)

This invention relates to cracking petroleum hydrocarbons into products suitable for motor fuel and pertains more particularly to a method of inhibiting coke deposition in vapor lines employed for transferring hot cracked vapor products to other parts of the cracking equipment wherein the cracked products are separated into the desired components.

Although the invention will have a more general application, it is of particular advantage in vapor phase cracking processes, and especially in high temperature cracking processes in which substantially the entire charge becomes vaporized during the cracking operation, in which case the products leaving the cracking zone are essentially in vapor phase.

In such processes operating difficulties have been experienced, due to coke accumulation in passages or conduits employed for transferring the hot cracked vapor products to subsequent equipment wherein separation and purification of the products is accomplished.

Attempts have been made to avoid coke deposition in the vapor passages by introducing into the passages a cooler oil of various types and character so as to reduce the cracked products to a temperature below that at which appreciable coking will occur. For example it has been proposed to introduce light vaporizable extraneous hydrocarbon oil into the hot vapor conduit and utilize the heat of vaporization of the extraneous oil to cool the products. However, in high temperature cracking processes the relatively large amount of extraneous vaporizable oil necessary to bring products to a temperature below that at which appreciable coking occurs imposes an extra heavy burden on the succeeding equipment employed for separation and purification of the products and has a disturbing influence on the temperature control of the succeeding equipment.

It has also been proposed to introduce into the hot cracked vapor products a relatively heavy hydrocarbon oil containing substantial amounts of constituents which will not be vaporized at the equilibrium temperature of the commingled products, so that the unvaporized liquid constituents of extraneous cooling medium may serve to flush or wash the coke thereafter formed from the conduit.

However, in high temperature vapor phase cracking processes coking troubles are encountered immediately adjacent the point of introduction of the relatively heavy residual stock due to the almost instant reversion of the heavier

constituents to coke when commingled with the high temperature vapor products.

In accordance with my invention, before introducing the relatively heavy residual stock to serve as a cooling and flushing medium for the coke or carbon thereafter formed, I rapidly cool the hot vapor products to a temperature at which the unvaporizable constituents of the residual stock will not substantially revert to coke and, after the preliminary cooling step, I immediately introduce a heavy residual stock so as to take advantage of the flushing or washing effect of the unvaporized constituents as soon as possible without causing rapid reversion of these constituents to coke. In carrying out the process in accordance with my invention the vapor products need not be preliminarily cooled to below cracking temperature before the introduction of heavy residual stock but need only be cooled to a temperature at which the heavy hydrocarbons introduced will not revert to coke. By way of example, I may rapidly cool cracked vapor products from a temperature of from 850° F. to 1100° F. or more to a temperature of from 800° F. to 950° F. and thereafter immediately introduce a relatively heavy stock having a component which will not be vaporized at the last mentioned temperatures but which will remain in liquid condition and thus serve to flush the vapor passage and wash away any carbon which may thereafter be formed and thus prevent any unobjectionable collection of carbon or coke in the system.

The initial cooling may be accomplished by direct or indirect heat exchange with a suitable cooling medium. However, in order to reduce coking difficulties within this preliminary cooling zone the cooling should be effected rapidly so as to require only a relatively short zone through which the hot, dry, cracked vapor products must pass before being intermingled with the heavy residual stock containing the unvaporizable constituents.

With the above and other advantages in view, which will be apparent from the more detailed description of the preferred embodiment herein-after, reference is now made to the accompanying drawings in which:

Figure 1 is a diagrammatic view in elevation showing an apparatus for carrying out a cracking process in which my invention may be employed, and

Figure 2 is a sectional view in larger scale of the vapor outlet leading from the reaction chamber.

Referring to Figure 1 the apparatus shown

comprises in general, heating furnaces 10 and 11; a reaction chamber 12; a separating chamber 13; a fractionating tower 14; a combined fractionating and distilling tower 15, condensers 16 and 17; 5 distillate receiving drums 18 and 19, together with connecting pipe lines, pumps and other appurtenant equipment for carrying out the process hereinafter described.

Fresh charging oil for the process which is 10 preferably crude petroleum, but which may be a reduced crude or heavy gas oil and which may be preheated by heat exchange with hot products of the process, is introduced into the combined distilling and fractionating chamber 15 through 15 line 20 provided with a charging pump 21. The charging oil introduced into the chamber 15 is heated to a distilling temperature by direct counter-flow contact with hot vaporized components from residual products withdrawn from 20 the separating chamber 13 through line 22, provided with a pressure-reducing valve 23. The hot residual products from line 22 are discharged after reduction in pressure into the bottom portion of the chamber 15 and are further vaporized 25 by reduction in pressure.

Uncondensed vapors formed in the distilling and fractionating chamber 15 pass overhead through line 24 to condenser 17 wherein a light gasoline distillate is condensed after which the 30 products pass to the separating drum 18 for separation of gases and distillate.

The unvaporized constituents of the fresh charging oil together with the heavier condensed vapors from the residual products and fresh oil 35 are collected in trapout tray 25 and passed through line 26, provided with a pump 27, to the heating coil 28 located in the furnace 11 wherein the charging oil is heated to a cracking temperature and maintained for a period adequate to effect 40 40 feet mild conversion and a material reduction in the viscosity of the charging stock. For example the oil during its passage through the heating coil 28 may be subjected to a temperature ranging from 800° F. to 850° F. for a period which will 45 convert about 8 or 10 percent of the oil into hydrocarbons within the gasoline range and about 20 or 25 percent into hydrocarbons suitable for vapor phase charging stock for the furnace 10.

The hot products leaving furnace coil 28 pass 50 through line 29 to the lower portion of the separating chamber 13, preferably without any substantial reduction in pressure. The separator is preferably operated at a substantial super-atmospheric pressure, say for example, between 55 195 and 215 pounds per square inch. The lighter hydrocarbon products formed in the heating coil 28 are separated from the residual liquid components of the charge as vapors and pass upwardly in such form through the separator 13 60 where they commingle with cracked vapor products from the reaction chamber 12.

The upper section of the separator 13 is provided with suitable fractionating elements such as 65 perforated baffle plates, disc and doughnut, screen-plates, or bubble trays to effect fractionation of the vapors and condense heavier components thereof. If desired a suitable refluxing agent such as light gas oil collected in the upper trapout tray 30 of the distilling and fractionating chamber 15 may be introduced into the upper portion of the separator 13 for knocking down entrained coke particles and heavy vapor constituents. Vapors remaining uncondensed in the separator 13 are withdrawn through vapor line 70 75 31 at a temperature of, for example, about 750°

F. to 760° F. and passed to fractionating tower 14 wherein further separation of the vapors into an overhead vapor fraction containing the gasoline constituents and a clean condensate fraction suitable for vapor phase cracking is effected. 5 To this end the fractionating tower 14 is provided with usual fractionating elements and, if desired, reflux agents such as a light gas oil from the trap-out tray 30 and/or gasoline distillate may be introduced into the upper portion 10 of the tower through line 32. This fractionating tower 14 is preferably maintained under substantially the same pressure as the separating chamber 13.

Vapors remaining uncondensed in the fractionating tower 14 and containing the gasoline component are withdrawn from the tower through vapor line 33 and passed to the condenser 16 in which the gasoline component is condensed. The products from condenser 16 discharges into 20 a separating and receiving drum 18 in which liquid and gases separate. The temperature at the top of the fractionating tower 14 is controlled so as to produce a gasoline having the desired end point such as 400° F. or thereabouts. 25 The condensate collecting in the bottom of the tower 14, which may be at a temperature of about 700° F., and which may have a specific gravity of about 25° A. P. I., a color corresponding to about 3 N. P. A. and a low free carbon content, preferably not over .1 percent by the Conradson test, is withdrawn through line 34, provided with pump 35 which forces the condensate through the vapor phase cracking coil 36 located in furnace 10 and thence through the 30 transfer line 37 to the lower portion of the reaction chamber or soaking drum 12.

The condensate during its passage through the heating coil 36 and the reaction chamber 12 is subjected to vapor phase cracking conditions, 40 preferably at a temperature in excess of 850° F. and more desirably at a temperature ranging from about 900° to about 950° F. while maintained at moderately low pressures such as from 195 to 225 pounds per square inch. The temperature and time of treatment within the cracking zone may be controlled so as to convert from about 15 to 20 or more percent of the condensate stock into gasoline during a single passage of the condensate through the cracking zone. At the 50 temperature and pressure so maintained substantially the entire charging stock is vaporized during the cracking process.

The vapors after being permitted to soak for the desired period within the reaction chamber 12 55 are withdrawn through the vapor outlet 38 and cross-fitting 39 and are passed thence through vapor line 40 to the bottom portion of the separator 13 where they commingle with the vapors liberated from the charge introduced into the separator from the line 29. The combined vapors are subsequently fractionated in the top of the separating chamber 13 and the fractionating tower 14 as hereinbefore described to produce the desired distillate product and reflux condensate. 60

My invention is not necessarily limited in its application to the oil cracking process hereinbefore described, this being an example of a type of cracking operation in which my invention has been found to be of advantage. As illustrated, 70 my invention is employed for the purpose of reducing coke difficulties in the vapor outlet 38 leading from the reaction chamber 12 and the vapor conduit 40 leading to the separating chamber 13.

Referring now to Figure 2, the hot cracked vapors leaving the reaction chamber 12 are preliminarily cooled by a spray of relatively light vaporizable oil introduced into the stream of vapor through spray ring 41 mounted in the reaction chamber 12 immediately adjacent the vapor outlet. As illustrated, a portion of the reflux condensate formed in fractionating tower 14 may be passed through lines 42 and 43 to the spray ring 41 to serve as a cooling medium or a light clean vaporizable stock or other vaporizable cooling medium such as water may be passed to the spray ring through lines 44 and 45. Ordinarily substantially all of the light oil is vaporized upon its admixing with the hot vapors leaving the reaction chamber 12 and is carried out by these vapors, any unvaporized portions of the light oil being entrained in the outgoing vapors. The vaporizable cooling medium may comprise substances other than hydrocarbon oil as before mentioned. The vapor after being preliminarily cooled by the vaporizable oil introduced through spray ring 41 is immediately commingled with a relatively heavy stock which is introduced into the stream through line 45 which extends through the cross-fitting 39 and terminates in a nozzle 46. The stock so introduced may be a crude, reduced crude, residual stock from the cracking operation, or any extraneous heavy stock which contains constituents which will remain in liquid form at the resulting temperature of the mixed products and thus serve to flush the remaining portion of the vapor line 40 of carbon particles.

As illustrated, a portion of the fresh charging stock such as crude or reduced crude being passed to the viscosity breaking furnace 11 through line 26 may be passed through lines 47 and 45 to the nozzle 46 or a portion of the cracked residual products from the bottom of the separating chamber 13 may be passed through line 48 to the line 45 and nozzle 46. Also if desired a mixture of cracked residual stock and crude or reduced crude may be introduced into the stream of vapors through the nozzle 46 and the lines above indicated. If desired an extraneous heavy stock containing unvaporizable constituents may be passed to nozzle 46 through lines 49 and 45.

Suitable cooling coils 50 and 51 may be provided in lines 42 and 45 respectively so that the cooling and quenching mediums taken from the system may be cooled to any desired extent before being introduced into the outlet of the chamber through the spray ring 41 and nozzle 46.

Sufficient vaporizable oil is introduced through the spray ring 41 to reduce the vapor products to a temperature which will not cause rapid conversion of the heavier constituents of the charge thereafter introduced through nozzle 46 into coke. The temperature need not be reduced, however, to below that at which coke will not subsequently be formed. The amount of oil introduced through the spray ring 41 and the nozzle 46 will depend upon the capacity of the unit, the temperature of vapor products and cooling medium, so that the exact amount can not be definitely specified. In a specific operation on a unit treating approximately 16,000 barrels of fresh oil per day and wherein the temperature at the top of the soaking drum was in the neighborhood of 885° F., the introduction of substantially equal amounts of stock through the spray ring 41 and through the nozzle 46 at a rate of approximately 60 barrels per hour respectively, was found ample to prevent coking troubles in the transfer line 40. The vapors were cooled by

the light oil to a temperature approximating 860° F. and thereafter cooled by the heavier stock introduced through nozzle 46 to a temperature of about 835° F.

To further reduce coking difficulties in the preliminary cooling zone in the vapor outlet 38 and in the soaking drum or reaction chamber 12 immediately adjacent the vapor outlet 38 I have shown a plunger 52 (see Figure 2) mounted in the cross fitting 39 which may be periodically reciprocated in the vapor outlet below the point of introduction of the heavy stock. Fluid actuating mechanism, comprising a cylinder 53 mounted on the cross fitting 39 and piston 54 slidably therein and connected by connecting rod 55 with the plunger 52, is provided for reciprocating the plunger. The cylinder 53 is provided with a port at each end which alternately serves as intake and exhaust ports for the actuating fluid. The actuating fluid may be a light hydrocarbon stock which may be subsequently discharged into the transfer line 40 as shown.

Although the invention has been described in connection with a conventional tube and drum type of cracking equipment, it will be clear that the invention is also applicable in tube cracking processes in which the digesting and soaking of the cracked vapors is accomplished in a coil or is completely dispensed with. In the latter process the preliminary cooling and subsequent introduction of heavy stock may be accomplished at the outlet of the heating coil or elsewhere in the line leading from the coil to the separating chamber. It will be further apparent that my invention will find application in other cracking processes and other parts of cracking equipment wherein hot vapor products above cracking temperature are transferred through a vapor line. For example, my invention will be of particular advantage in short-time, high-temperature cracking processes in which the cracking stock is subjected to extremely high cracking temperature, such as for example 1100° F. or more for an extremely short period, measured in seconds or fractions of seconds. In such operations, according to my invention the hot vapor products at the extremely high cracking temperature is rapidly cooled to a temperature which will not cause rapid conversion of heavy constituents to coke and the vapor products thereafter immediately intermingled with a stock containing unvaporizable constituents before the vapor products pass to subsequent equipment for separation and purification.

Having described the preferred embodiment it is understood that my invention embraces such other variations and modifications as fall within the scope and spirit thereof and that the invention is not intended to be limited except as necessary to distinguish from prior art.

I claim:

In the art of cracking hydrocarbon oils wherein a body of oil vapors is maintained at cracking temperature in an enlarged reaction chamber and vapors are withdrawn from said reaction chamber through a conduit to a subsequent enlarged zone for fractionation, the improvement which comprises subjecting the vapors passing to the subsequent fractionating zone to a double cooling operation by initially introducing into the hot vapors passing from the enlarged reaction chamber a vaporizable liquid material to thereby reduce the temperature of the vapors and by immediately thereafter introducing into the resultant stream of cooled products in the

conduit immediately adjacent the point of introduction of said vaporizable liquid medium a heavy oil stock of the nature of reduced crude comprising unvaporizable constituents to thereby further reduce the temperature of the products flowing through the conduit and prevent

coking therein, but not lower the temperature below a cracking temperature, and delivering the products from the conduit to the subsequent fractionating zone at a cracking temperature.

HOWARD DIMMIG.
